M. O. GOLDSMITH

ROLLER WINDOW SCREEN

Filed April 13, 1925

UNITED STATES PATENT OFFICE.

MAURICE O. GOLDSMITH, OF BOSTON, MASSACHUSETTS.

ROLLER WINDOW SCREEN.

Application filed April 13, 1925. Serial No. 22,574.

The principal object of my invention is to provide a roller window screen which, when in use, will be held firmly at its side edges and my object more particularly is to do 5 such holding by mechanism which will be simple and effective.

A feature of my invention is that the screen itself keeps the holding means out of holding engagement while the screen is moving.

Another feature is that the means for moving the holding means out of holding position is carried by the screen itself.

Another feature is that the holding means 15 moves automatically into holding position when the screen is fully unrolled.

Other features will be pointed out below.

Figure 1 is a partial elevation partly in section of a portion of a window equipped 20 with my invention;

Figure 2 is a section on line 2—2 of Figure 1;

Figure 3 is an enlarged sectional detail 25 on the line 3—3 of Figure 1;

Figure 4 is a section on line 4—4 of Figure 1; and

Figure 5 is a detail hereinafter described.

The window with which my screen may be used may be of ordinary construction 30 and may comprise the frame A, the sill B, the upper sash D and the lower sash E.

Suitably fixed to the frame is a box F having an end wall f with a rectangular slot f', there being a similar wall at the other 35 end of the box. Pintle G is provided with a rectangular extension g to enter slot f' and has fixed to it at g' one end of coiled spring g². This spring is operatively connected in any well known way to the roller H and 40 tends to roll up the wire screen J, the latter being fixed to the roller at j.

Fixed to the bottom of the screen, at the front thereof, is a plate K, preferably held to the screen and to the rear plate K' by 45 rivets k. A finger piece, whose function will be described below, is pivoted to plate K at l and comprises upper portion L and lower portion L' the latter having a lug at l' to be raised by the user, the weight or portion L' 50 tending to hold that portion normally against stop l². A similar finger piece (not shown) is pivoted to the opposite end of plate K.

An angle iron comprising portions M and 55 M' is suitably held in place, the portion M providing a face against which one side edge

of the screen is clamped as described below and the portion M' forming a support for brackets m and m', which are held in place by screws, which screws may also hold portion M' to the window frame.

Brackets m and m' are perforated to form pivot bearings for the ends of shaft N² which is rigidly secured to angle iron N N', said ends projecting above and below said angle iron N N' in order to enter the perforations in the brackets. Portion N has an eye n connected to coiled spring n' which in turn is connected to eye n² fixed to portion M (as clearly appears in Figure 4) and therefore spring n' tends to force portion N' to the right in Figure 4 so as to clamp the side edge of the screen firmly in place in order to exclude insects or other undesired objects.

It will be noted that portion N' is at an 75 angle with portion M with the result that any pull on the screen in a direction to the right in Figure 4 will tend to increase the clamping action.

Similar springs n³ and n⁴, similarly 80 mounted, are provided and, of course, any desired number might be used.

Portion N' is notched at n⁵ to receive one end of plate K, the upper end of the notch forming a shoulder to prevent undesired 85 upward movement of plate K and consequently of screen J.

It will be understood that for the other side edge of the screen I provide similar sets of angle irons and cooperating springs.

The screen is held unrolled, as in Figure 1, principally by the engagement of member K with the top wall of the recess or notch n⁵ although, if desired, the strength of the springs n³, n' and n⁴ may be such as to 95 clamp portions N' against the screen. When it is desired that the screen be rolled up the lugs l' are raised with the result that portions L are forced outwardly and press portions N' toward portions M' so that the 100 notches n⁵ are moved out of the path of portion K and consequently the screen may be rolled up. During the upward movement the portions L may be held in their outward 105 positions or the fingers of the user may be removed from the lugs l' and the screen may be pushed up at the middle portion K and in such case the ends of portion K will hold portions N' out of engagement with the screen and said portions will be pushed 110 so far toward portions M' that there will be substantially no clamping action of portions

N' on the ends of portion K. The result is that the screen may be rolled up until the lugs l' engage the bottom of box F where the screen will remain until it is desired to unroll it. When the screen is rolled up the portion K will be above the tops of portions N'.

When the screen is to be unrolled the portion K is pulled downward and the curved portion l' will engage the top of portion N' (and of the corresponding portion N' at the other side of the window) and will force these portions toward the portions M' so that portion K may be moved down and the screen unrolled until portion K is opposite notch n^o whereupon the vertical edges of portions N' automatically move against the screen and hold it against the inner faces of portions M so that all undesired things will be excluded.

I prefer to have the member K' extend clear across the screen as does member K and member K' is preferably to be curved at its lower corners like the curving of member K.

What I claim is:

1. A device of the character described comprising a roller screen; means to hold the side edges of said screen in place when the screen is in an unrolled condition; resilient means having an operative connection with a fixed portion of the device and tending to hold said holding means in engagement with the screen; and means carried by the screen to move said holding means to permit rolling of the screen.

2. A device of the character described comprising a screen; a roller for the screen; means tending to roll up said screen on the roller; means to hold the side edges of the screen in place when the latter is in an unrolled condition; resilient means having an operative connection with a fixed portion of the device and tending to hold said holding means in engagement with the screen; and a member fixed to and carried by the screen and engaging said holding means to prevent undesired rolling up of the screen.

3. A device of the character described comprising an angle-iron having one inner face to engage the screen when the latter is in an unrolled condition and another inner face to support bearings; said bearings; another angle-iron pivoted in said bearings and having an edge at one side of the pivot to hold the screen against said one inner face; and resilient means connected with said other inner face of the first-mentioned angle-iron and connected with said other angle-iron at the other side of its pivot, said resilient means tending to hold said edge against the screen and the latter against said inner face.

4. A device of the character described comprising an angle-iron having one inner

face to engage the screen when the latter is in an unrolled condition and another inner face to support bearings; said bearings; another angle-iron pivoted in said bearings and having an edge at one side of the pivot to hold the screen against said one inner face; and resilient means connected with said other inner face of the first-mentioned angle-iron and connected with said other angle-iron at the other side of its pivot, said resilient means tending to hold said edge against the screen and the latter against said inner face; and means to move said edge out of holding position preparatory to rolling the screen.

5. A device of the character described comprising an angle-iron having one inner face to engage the screen when the latter is in an unrolled condition and another inner face to support bearings; said bearings; another angle-iron pivoted in said bearings and having an edge at one side of the pivot to hold the screen against said one inner face; and resilient means connected with said other inner face of the first-mentioned angle-iron and connected with said other angle-iron at the other side of its pivot, said resilient means tending to hold said edge against the screen and the latter against said inner face; and means carried by the screen to hold said edge out of holding position during the rolling of the screen.

6. A device of the character described comprising an angle-iron having one inner face to engage the screen when the latter is in an unrolled condition and another inner face to support bearings; said bearings; another angle-iron pivoted in said bearings and having an edge at one side of the pivot to hold the screen against said one inner face; and resilient means connected with said other inner face of the first-mentioned angle-iron and connected with said other angle-iron at the other side of its pivot, said resilient means tending to hold said edge against the screen and the latter against said inner face; means to move said edge out of holding position preparatory to rolling of the screen; and means to hold said edge out of holding position during the rolling of the screen.

7. A device of the character described comprising a screen; a roller for said screen; fixed bearings for said roller; means mounted on vertical pivots to hold the edges of the screen in the desired position when the screen is in use; resilient means having an operative connection with a fixed portion of the device and tending to hold said holding means in engagement with the screen; and a member fixed to the screen to move said holding means to permit unrolling of the screen.

8. A device of the character described comprising a screen; a roller for said screen;

fixed bearings for said roller; means to hold the edges of the screen in the desired position when the screen is in use; a resilient means having an operative connection with a fixed portion of the device and tending to hold said holding means in engagement with the screen; and a member fixed to the screen and operative to move said holding means to permit unrolling of the screen.

9. A device of the character described comprising a screen; a roller for said screen; fixed bearings for said roller; means mounted on vertical pivots to hold the edges of the screen in the desired position when the screen is in use; resilient means having an operative connection with a fixed portion of the device and tending automatically and always to keep said holding means in holding position; and means to move said holding means to permit rolling of the screen.

10. A device of the character described

comprising a fixed face; a member pivoted on a vertical axis and having a vertical edge to engage the edge of the screen throughout the greater part thereof; and resilient means tending to hold said vertical edge against said screen and the latter against said face when the screen is in an unrolled condition; said vertical edge, when in normal engagement with the screen, being further from the vertical centre of the window than is the plane extending through said pivot at a right angle to said face, the distance from the pivot of said member to said vertical edge being such that when the vertical edge is holding the screen against said face said edge can not swing past the point on said face which is nearest to said pivot, said resilient means tending to force said vertical edge toward said point to increase the holding action on the screen.

MAURICE O. GOLDSMITH.
